RIDGE COUNTER APPLIANCE

Norman A. Compton, Suitland, Md.

Application September 15, 1943, Serial No. 502,520

7 Claims.

(Cl. 120—84)

This invention relates to a ridge counter appliance, and it is primarily an object of the invention to provide an appliance of this kind to facilitate the work in connection with the finger-print classification.

At the present time in connection with finger-print classification, it is the general practice of the classifier to use a pencil or other writing implement and also a separate instrument known as a ridge counter. The writing implement and the counter are entirely separate and in the work of classification it is required that either the writing implement or the counter be picked up and set down with great frequency which often results in annoyance and inconvenience to the classifier. Furthermore, in view of these many separate and frequent operations of picking up and setting down the writing implement and the counter, the classifier will neglect to use the ridge counter but will employ the point of the writing implement in lieu thereof and which is liable to reduce the standard of the reading. Another object of the invention is to provide an appliance which will substantially eliminate these disadvantages.

A further object of the invention is to provide a ridge counter appliance which is carried by the writing implement, thus assuring the classifier having readily available both of the instruments for immediate use as required.

The invention consists in the details of construction and in the combination and arrangement of the several parts of my improved ridge counter appliance whereby certain important advantages are attained, as will be hereinafter more fully set forth.

In order that my invention may be better understood, I will now proceed to describe the same with reference to the accompanying drawing, wherein:

Figure 1 is a view in side elevation illustrating a ridge counter appliance constructed in accordance with my invention and in applied position;

Figure 2 is a view in top plan of the structure as illustrated in Figure 1;

Figure 3 is a view partly in side elevation and partly in section of the device;

Figure 4 is a view similar to Figure 3 but showing the ridge counter in a second position;

Figure 5 is a sectional view taken substantially on the line 5—5 of Figure 1; and

Figure 6 is a fragmentary view partly in section and partly in elevation illustrating a slightly modified form of the invention.

As illustrated in the accompanying drawing, P denotes a conventional writing implement, such as a pencil, and upon which the improved appliance A is mounted. As illustrated in the accompanying drawing, the mounting of said

appliance is such that the same may be readily retracted along the pencil P as the pencil shortens in length as the result of sharpenings but normally maintains the appliance A in substantially a fixed position.

As herein disclosed, the appliance A includes an elongated body 1 of metal or other preferred material and of required dimensions. The body 1 is provided at its extremities with the transversely spaced spring clips 2 which are adapted to straddle the implement P when the attachment is applied thereto and to have sufficient frictional contact with the implement P to hold the body 1 normally in a substantially fixed position yet permitting the body 1 to be shifted along the implement P when the requirements of practice necessitate.

The forward portion of the body 1 is provided with a bore 3 open at the front and having its rear end open and in communication with the longitudinally disposed slot 4, the rear end of which is open.

The ridge counter C comprises an elongated strand of material, such as steel wire of desired gauge and possessing a certain degree of inherent resiliency. The rear portion 5 of the counter C is substantially straight and extends through the bore 3 of the body 1 and into the slot 4. The extremity of the portion 5 of the counter C within the slot 4 is formed to provide a laterally disposed arm 6 of a length to extend beyond the outer face of the body 1. Carried by the outer or free extremity of this arm 6 is the button 7, the outer face of which is preferably concaved.

The forward or outer end portion 8 of the counter C is normally disposed on a gradual curvature and such curved portion 8 is of such length that when the counter C is extended for use, the pointed extremity 9 is at substantially the axial center of the writing implement P or in substantial alignment with the writing point 10 of the implement P.

When the counter C is not in use, it can be readily retracted inwardly beyond the writing point 10 of the implement P by imposing rearward pull on the button 7 which can be readily done by a digit of the hand holding the implement P. As the counter C is retracted, the inherent resiliency of the counter C, or more particularly the curved portion 8 thereof, will allow said portion 8 to readily ride up and along the implement P to a point inwardly of the writing point 10. When the counter C is extended for use, the inherent resiliency thereof will result in the same returning the pointed extremity 9 thereof into the position hereinbefore pointed out.

By having the outer end of the slot 4 open, the application or removal of the counter C with respect to the body 1 may be readily effected

and this is desirable particularly when it is deemed necessary to replace a counter C.

The extent of projection or forward movement of the counter C is limited by contact of the arm 6 with the inner or closed end of the slot.

In the event it may be desired to limit the extent of retraction of the counter, in the embodiment of the invention illustrated in Figure 6 the outer end of the slot 11 is closed, as at 12, and by contact of the lateral arm 14 of the ridge counter R, the inward or retracting movement of the counter R will be limited.

The forward end of the body 1 is provided with a forwardly and inwardly disposed spring leaf or arm 15 which contacts with the counter C in a manner to provide sufficient friction to normally hold the counter C against endwise movement with respect to the body 1.

From the foregoing it is thought to be obvious that a ridge counter appliance constructed in accordance with my invention is particularly well adapted for use by reason of the convenience and facility with which it may be assembled and operated.

What is claimed is:

1. The combination with a marking implement such as a pencil, of a body designed to be mounted upon the implement, said body having a guide slot therein which extends longitudinally of the implement when the body is mounted upon the implement, a stylus having a shank portion slidably mounted in the slot, means carried by the shank portion for engagement with a finger of the hand holding the marking implement to effect the reciprocal movement of the stylus with respect to the body and the marking implement, and said stylus being longitudinally curved through a portion of its length to the end remote from the shank, the curvature of the stylus being towards the longitudinal center of the marking implement and of such extent that when the stylus is shifted forwardly to project the point of the stylus beyond the marking point of the implement, the point of the stylus will assume a position upon the longitudinal center of the marking implement beyond the point of the latter.

2. An instrument of the character stated, comprising a relatively long body, means for mounting the body longitudinally upon a carrier such as a pencil, the body having a longitudinally extending recess therein, a relatively long stylus having a straight shank portion slidably mounted in the recess and a longitudinally curved portion extending to the point of the stylus, the shank having a laterally turned terminal portion extending outwardly from the slot, a button carried by the shank for engagement by a finger of the hand carrying the marking implement, said stylus curvature being of a sufficient degree and in a direction to bring the point of the stylus to the longitudinal center of the carrier when the stylus is shifted to a position where the point thereof lies beyond an end of the carrier.

3. An instrument of the character stated, comprising a body, means for mounting the body upon a carrier such as a pencil, the body having a guide slot formed therein and extending through a portion of its length and a bore leading from an end of the slot through the body to and through an end of the body, a stylus having a shank slidably extended through said bore,

the shank having a laterally turned terminal portion lying in the slot and extending outwardly therefrom, said slot and bore extending longitudinally of the carrier when the body is mounted on the carrier, a finger button carried by the lateral extension for engagement by a finger of the hand holding the carrier whereby reciprocal movement of the stylus by such finger may be effected, and resilient frictional means carried by the body and engaging the stylus for maintaining the stylus in a desired position.

4. An instrument of the character stated, comprising a body, means for mounting the body upon a carrier such as a pencil, the body having a guide slot formed therein and extending through a portion of its length and a bore leading from an end of the slot through the body to and through an end of the body, a stylus having a shank slidably extended through said bore, the shank having a laterally turned terminal portion lying in the slot and extending outwardly therefrom, said slot and bore extending longitudinally of the carrier when the body is mounted on the carrier, a finger button carried by the lateral extension for engagement by a finger of the hand holding the carrier whereby reciprocal movement of the stylus by such finger may be effected, and a resilient finger integral with the body and extending therefrom adjacent to the bore and having frictional contact with the stylus to maintain the stylus in a desired position.

5. The combination with a relatively long pointed marking implement, of a stylus having its pointed end arcuate, and means slidably connecting the stylus with the implement for longitudinal movement thereon for the extension of the stylus point to a position in advance of the implement, the stylus being so positioned relatively to the body of the implement when in the first mentioned position as to have its point in the line of the longitudinal axis of the implement.

6. The combination with a relatively long pointed marking implement, of a stylus having a relatively long shank portion and longitudinally curved at its pointed end, means coupling said shank to the side of the marking implement with the shank extending parallel to the implement and the pointed end of the stylus disposed adjacent to the pointed end of the implement, said coupling means being of a character to facilitate the longitudinal movement of the stylus on the implement to an extent sufficient to position the stylus point in advance of the point of the marking implement, and said coupling means and the degree of curvature of the stylus co-acting to locate the stylus point in the longitudinal axis line of the implement when the stylus is shifted to a position to locate the point thereof in advance of the point of the implement.

7. The combination as set forth in claim 6, in which the stylus is formed of resilient material, and means frictionally contacting the side of the stylus remote from the marking implement and maintaining the stylus in proper position relative to the marking implement when the stylus is shifted in a direction to bring the point thereof to the stated position in advance of the point of the marking implement.

NORMAN A. COMPTON.
